UNITED STATES PATENT OFFICE

159,453

GAME BOARD

Anna V. Wagner, Chicago, Ill.

Application November 15, 1949, Serial No. 6,040

Term of patent 7 years

(Cl. D34—5)

To all whom it may concern:

Be it known that I, Anna V. Wagner, a citizen of the United States, residing at Chicago, in the county of Cook and State of Illinois, have invented a new, original, and ornamental Design for a Game Board, of which the following is a specification, reference being had to the accompanying drawing, forming part thereof, in which—

Fig. 1 is a top plan view of the game board showing my new design, and

Fig. 2 is a side elevational view thereof.

I claim:

The ornamental design for a game board, substantially as shown.

ANNA V. WAGNER.
